UNITED STATES PATENT OFFICE.

GEORGE CHRISTENSON, OF NORTH PLAINFIELD, NEW JERSEY, ASSIGNOR TO JOHNS-MANVILLE INCORPORATED, OF NEW YORK, N. Y., A CORPORATION OF NEW YORK.

PACKING FOR PUMP PLUNGERS.

Application filed January 24, 1925. Serial No. 4,629.

My invention relates to the construction of packings for pump plungers and particularly to packings for swabbing plungers which are used for raising oil from a deep oil well. For this service the practice is to lower a pump plunger into a sectional oil pipe to a depth estimated to be considerably below the level of oil in the well and then raise the plunger with its superincumbent load of oil to the ground surface.

By reason of the inevitable roughness and irregularities in the oil pipes in common use the packings of plungers used for this duty have been short lived. The causes of accident and injury to such plunger packings are quite diverse and sometimes unexpected so that structural features of packings intended or adapted to provide against the more usual contingencies may prove inadequate when encountering the unexpected.

The object of the improvements herein described is to arm such a plunger packing at all points and in such manner as to insure it against injury from abnormal impacts or abrasions from any quarter. Structural provisions made with such intent must be consistent with the retention by the packing as a whole of a proper measure of flexibility and elasticity and consistent also with the retention of those qualities which render the packing fluid-tight and capable of withstanding the very considerable fluid pressures which develop in use.

In the drawings hereto annexed which illustrate my improvements,

Fig. 1 shows in vertical section a portion of an oil well pipe, a swab plunger head, and three packing members;

Fig. 2 shows on a larger scale one of the packing cones in vertical section; and

Fig. 3, on the same scale as Fig. 2, shows a cone in top plan view.

In the drawings, A represents a section of an oil well pipe and G a coupling member by which one section is attached to another. Usually an annular space such as H is left between the ends of adjacent pipe sections, and such spaces, together with original irregularities in the interior of the pipes,

dents produced by accident, etc., are among the features incidental to oil well practice which call for special protective devices in the packing members of an oil well swab. B designates generally a tubular swab head which is composed of sections B¹, these sections being screwed together endwise when the head is assembled forming a tubular member open at both ends, one end provided with a section at B³ which may serve for the attachment of the hoisting cable and the other end a suitable check valve as V for the admission of oil to and its passage through the head as the latter is lowered. Each of the sections B¹ is provided with an exterior shoulder B⁴ between which and the threaded end of the adjacent section the calyx C is rigidly and securely held. This calyx, which constitutes the seat and lower support for the packing member is preferably frustoconical in shape, having a flaring lip C¹. The packing member D is a tubular cone shaped body interiorly shouldered at D² and exteriorly shouldered at D³ (See Fig. 2). The interior shoulder engages with a complementary ledge on the tubular head section B¹ and the exterior shoulder D³ with the upper edge of the calyx lip C¹. The packing member D is conical in shape and will therefore be referred to as a cone of which the body consists of hard rubber composition or like material which possesses elasticity and flexibility operative within the rather narrow required limits to permit occasional distortion of the cone from its normal shape, and to restore itself when the distortive force is removed. Preferably the interior of the cone is of such dimensions as to form a clearance between the cone and the plunger stem which it surrounds. This clearance is preferably provided by molding the cone with an interior conical surface. For protection an assemblage of protector plates such as E, which may be made of sheet steel, radially disposed and circumferentially spaced, are lodged in the material of which the cone is composed. Each of these protector plates E has a notch or shoulder at E¹ which coincides in position with the annular shoulder

2
 D³ upon the cone D and is likewise adapted to engage with the upper edge of the lip C¹ of the calyx C. Preferably also each of the protector plates has an inwardly extending projection E² which provides additional security of anchorage of the plate in the body of the cone D. The preferred manner in which to assemble the protector plates in the cone is to arrange the plates in the mold in 10 which the cone is formed so that the plates may thus be the more securely embedded in the material of the cone.

The upper middle portion of the cone and likewise the exposed edges E³ of the 15 protector plate lie in a substantially cylindrical surface so that this edge or portion of the packing which normally engages the interior wall of the oil pipe will have a sufficiently large area of contact therewith. The upper 20 ends of the plates at E⁴ and likewise the corresponding surface of the cone B are inwardly tapered or rounded. The elastic and yielding material of the cone D preferably extends upward as a relatively thin and 25 flexible lip D¹.

Guard plates F of rigid material are secured, as by shrinking or burring, to the plunger head sections, each guard plate lying immediately over the upper lip D¹ of a 30 packing cone with its depending outer flange F¹ surrounding the upper end of said cone. This flange F¹ should normally approach quite closely to the upper ends of the protector plates E for a purpose hereinafter 35 to be mentioned. The guard rings F as at points F² provide aperture communication to the clearance space between the cone D and the plunger head section B¹.

By means of the construction above described, both of the packing member itself and its immediate associated adjuncts, shocks or pressures tending to compress, distort or dislodge the packing member longitudinally are resisted by the shoulder engagement 40 both of the cone body and the protector plates with the lip C¹ of the calyx C, the hook engagement of the protector plate with the body of the cone at E² guarding against relative longitudinal displacement 45 of the protector plate and flexible cone body; at the other end longitudinal disarrangement or distortion is guarded against by the close proximity between the flange F¹ of the guard ring and the upper ends 50 of the protector plates. Components of pressure or impact directed inwardly are rendered harmless by the readiness of the cone D to yield inwardly in radial directions. The steel protector plates by reason 55 of their hard material and their exterior conformations serve as skids which assist the packing member to pass obstacles in the pipe and protect the softer material of the cone against serious abrasions. Since the 60 cone should be permitted to expand out-

wardly in order to maintain contacts with the inner wall of the oil pipe and yet should be protected against the effect of too great expanding pressure, the relatively yielding and elastic lip D¹ in cooperation with the 70 encircling flange F¹ of the guard ring is provided to meet these requirements. When these two named members are in actual contact the pressure on the interior of the cone will be permitted by reason of the limited 75 flexibility and elasticity of the cone material to expand the cone as a whole to a slight degree when such expansion is required to maintain local fluid-tight contact 80 between the cone and the oil pipe; but undesirable response to expanding pressure is effectively checked by the restraining influence of the flange F¹.

I claim:

1. A packing for oil well plungers of the 85 character described, comprising a relatively rigid calyx, a tubular cone of relatively flexible material, and protector plates of relatively hard material, radially disposed, circumferentially spaced, lodged in the body 90 of the cone with their outer edges exposed, said plates provided with shoulders to engage the lip of the calyx.

2. A packing for oil well plungers of the 95 character described, comprising a relatively rigid calyx, a tubular cone of relatively flexible material, said cone at one end adapted to be seated in the calyx, and provided with a shoulder to engage the lip of the calyx, and protector plates of relatively hard material, radially disposed, circumferentially spaced, lodged in the body of the cone with their outer edges exposed, said plates provided with shoulders to engage the lip of the calyx.

3. A packing for oil well plungers of the 100 character described, comprising a relatively rigid calyx, a tubular cone of relatively flexible material, and protector plates of relatively hard material, radially disposed, circumferentially spaced, lodged in the body of the cone with their outer edges exposed, said plates provided with shoulders to engage the lip of the calyx, and with retaining 105 extensions projecting inwardly in the cone material.

4. A packing for oil well plungers of the 110 character described comprising a relatively rigid calyx, a tubular cone of relatively flexible material, and protector plates of relatively hard material, radially disposed, circumferentially spaced, lodged in the body 115 of the cone with their outer edges exposed, said plates provided with shoulders to engage the lip of the calyx and extending therefrom to points near the end of the cone remote from the calyx.

5. A packing for oil well plungers of the 120 character described, comprising a relatively rigid calyx, a tubular cone of relatively flex-

ible material, protector plates of relatively hard material, radially disposed, circumferentially spaced, lodged in the body of the cone with their outer edges exposed, said plates provided with shoulders to engage the lip of the calyx, said cone adapted to be seated at one end in the calyx, and at the other end free, and a guard of rigid material adapted to engage with the free end of the cone and with the ends of the protector plates.

Signed by me at Manville, N. J., this 19th day of January, 1925.

GEORGE CHRISTENSON.
